[57] ABSTRACT

An internal combustion engine comprising a block providing four equiangularly arranged cylinders opening toward a common center, a piston reciprocable in each cylinder, each piston comprising a main body formed at its outer end with an outwardly tapering port, and a plug for closing the tapered port at times, a first drive piston reciprocable across the common center and cooperative with one diametrically opposed pair of plugs, a second drive piston reciprocable across the common center and cooperative with the other diametrically opposed pair of plugs, a link connected at one end to the first drive piston and connected at its other end to the second drive piston, a rotor mounted on an axis which is perpendicular to the plane which is common to the axes of the cylinders, and a pivot connecting the midportion of the link eccentrically to the rotor to drive the rotor when the drive pistons are reciprocated in sequence.

1
ENGINE

The present invention relates to an engine which may be pneumatically or hydraulically actuated but which is primarily designed to be an internal combustion engine. It has been specifically illustrated and will be described, therefore, as an internal combustion engine although it is to be understood that it may electively be driven either hydraulically or pneumatically.

The primary object of the invention is to provide a small, light, inexpensive internal combustion engine which shall be unusually powerful in relation to its size and weight. A further object is to provide such an engine in which each cylinder will fire once during each rotational cycle of its output shaft.

Another object of the invention is to provide an engine of the character described but including two drive pistons, each arranged to cross the path of the other twice during each revolution of the output shaft. A still further object of the invention is to provide, in such an engine, a piston structure consisting of a main piston body open at its inner end and having a port at its outer end, together with a plug for each piston port, the plug being so constructed and arranged that, during the compression stroke and during a major portion of the power stroke of the composite piston, the plug will close the piston port, and the plug will reopen the piston port only after the piston body has been stopped and the associated cylinder is to be exhausted of products of combustion.

Still further objects of the invention will appear as the description proceeds.

To the accomplishment of the above and related objects, this invention may be embodied in the form illustrated in the accompanying drawings, attention being called to the fact, however, that the drawings are illustrative only, and that changes may be made in the specific construction illustrated and described, so long as the scope of the appended claims is not violated.

In the drawings:

FIG. 1 is a sectional view of my engine taken substantially on the plane which is common to the axes of the four cylinders;

FIG. 2 is a sectional view taken substantially at right angles to the plane of FIG. 1;

FIG. 3 is a somewhat simplified section showing an intermediate position of the parts after an explosion in the combustion chamber of the upper cylinder;

FIG. 4 is a similar view taken after an explosion in the lowermost cylinder;

FIG. 5 is a similar view taken after an explosion in the right-hand cylinder; and

FIG. 6 is an enlarged, fragmentary section illustrating details of a check valve in a fuel inlet passage.

Referring more particularly to the drawings, and primarily to FIG. 1, it will be seen that I have illustrated a block 10 formed with a bore 11 counterbored to define an outwardly-facing step 12 and a further outwardly-facing step 13. A cylindrical sleeve 14 bears on the step 12 and the block is formed with a through bore 15 coaxial with the bore 11.

A cylindrical shell 16 rests on the step 12 and snugly surrounds the sleeve 14. A composite piston comprises a main body 17 open at its inner end and formed with an outwardly-tapered port 18 in its outer end. A plug 19 conforming to the shape of the port 18 and having a skirt 20 is shorter than the piston body 17 and is reciprocably received therein.

2

A drive piston 21 is reciprocable in the through bore 15 and, in the positions of the parts illustrated in FIG. 1, bears against the plug 19 to hold the same in port-closing position.

5 A head 22 threaded onto the body 10 is provided with a threaded bore 23 opening into the combustion chamber above the piston 17 for the reception of a conventional igniter, such as a spark plug.

Concentric with the sleeve 14 and symmetrically opposed thereto is a sleeve 24 in which is reciprocably guided a second primary piston 25 which is open at its inner end and is provided at its outer end with a concentric, tapered port 26. A plug 27 similar to the plug 19 is reciprocable within the primary piston 25 to close the port 26, at times.

Ninety degrees removed from the above-described cylinders is a fourth cylinder partially defined by the sleeve 28 in which is reciprocably received the primary piston 29 having a tapered port 30 at its outer end. The 20 plug 31 which is shorter than the piston 29 is reciprocably received within said piston and is movable to a position in which it closes the port 30.

Diametrically opposite the sleeve 28 is a further sleeve 32 defining a cylinder in which the primary piston 33 is reciprocable. The piston 33 is formed to provide an outwardly-tapering port 33' with which cooperates a plug 34 which is reciprocable within the piston body 33.

30 A second drive piston 35 is reciprocable within the through bore 36 which intersects the through bore 15 at its midpoint. Links 37 and 42 are pivoted at one end substantially to the midpoint of the drive piston 21 by means of a pivot 38; and said links are similarly connected at their other ends to the drive pinion 35 by means of a similar pin 39. Substantially at the midpoint of the length of the links 37 and 42, a stud 40 is fixed to said links and preferably carries an antifriction roller 41. Similarly, a stud 43 projects in the opposite direction and may carry an antifriction roller 44.

40 A disc or plate 45 is journaled in a suitable recess 49 in the block 10 and is perforated to register with an eccentric socket 46 in the base of a rotary cam 47, said cam base being suitably secured to the plate 45 by means of screws 48 or other equivalent fastening means.

45 The antifriction roller 44 on the stud 43 is similarly received in a socket 54 in the base of a gear or sprocket 55, a plate 53 formed with a suitable aperture being journaled behind the member 55, secured to that member by screws 56 or other suitable fastening means and turning with said member 55 within a socket 57 formed in the block 10.

50 As will be explained more fully hereinafter, as the drive pistons 21 and 35 are caused to reciprocate in sequence, the pins 40 and 43 will travel in a circle. Since those pins are engaged in the eccentric sockets 46 and 54 in the rotor elements, such travel of the pins 40 and 43 will cause synchronous rotation of the elements 47 and 55.

55 Each cylinder is provided with an intake port 60, 61, 62, 63 defined partly in the shell 16 and partly in the sleeve 14. As is most clearly illustrated in FIG. 6, the port portion formed in the sleeve 14 is a perimetral external grooved opening at one or more points through the inner surface of the sleeve, while the port portion formed in the shell 16 is outwardly tapered; and a ball valve 64 is received in said port to close against the

taper under the influence of pressure within the associated cylinder.

The block walls are formed with inlet passages 65, 66, 67 and 68 constantly in registry with the respective ports 60, 61, 62 and 63; and one or more exhaust ports 69 will be formed through each of the plugs 19, 34, 27 and 31.

Fuel is fed to the several intake passages from a carburetor 70 through a pump 71 and thence through valves 72, 72 suitably actuated by cam followers 73 dominated by the rotary cam 47.

Operation

With the parts in the positions of FIG. 1, let us assume a compressed fuel charge in the combustion chamber 74 and an uncompressed fuel charge in the combustion chamber 75. When ignition takes place in chamber 74, the piston 17 will be moved downwardly. Drive piston 21, being currently in contact with plug 19, will thereby be moved downwardly to move the linkage 37, 42; and the engagement of the pins 40 and 43 with the rotors 47 and 55 will cause the linkage to move the drive piston 35 to the left. Drive piston 35 promptly encounters plug 34 to move the same into closing relation with the port 33', whereafter continued movement of the drive piston 35 to the left will carry with it the piston 33 to compress the fuel charge in the chamber 75.

At about the same time, the piston 17 will encounter the stop 13; but the plug 19 will continue to move downwardly under the influence of the expanding gases in the chamber 74. Such downward movement of the plug 19 relative to the piston 17 will open the exhaust passages 69 in said plug to permit gases of combustion to escape to the interior of the block and thence, through exhaust ports 78, to the atmosphere.

At the instant of ignition, the piston 17 seals the fuel intake ports 60; but as said piston clears said ports, the internal pressure within the chamber 74 will close the ball valves 64. When the plug 19 encounters the stop 13, further inward movement of said plug will, of course, be stopped; but the drive piston 21 will continue to move downwardly until the drive piston 35 attains the left-hand limit of its stroke, when the drive piston 21 will be stopped in a median position bridging the through bore 36.

Now, the compressed fuel in the combustion chamber 75 will be ignited and the piston 33 and plug 34 will be driven toward the right. The drive piston 21 will thereby be caused, in the manner above described, to move downwardly in the through bore 15 to engage and entrain the plug 27. Meantime, a fuel charge will have been injected into the chamber 76 and, as the plug encounters and closes the port 26, the piston 25 will be entrained to compress the charge in the chamber 76. As the piston 25 moves to the end of its stroke, the drive piston 35 will stop in bridging relation to the through bore 15. Exhaust from the chamber 75 will occur in the manner above described.

Meantime, a charge of fuel will be injected into the chamber 77 and, when the charge in the chamber 76 is ignited, the parts will move in the manner above described through an intermediate position illustrated in FIG. 4 to a position in which the charge in the chamber 77 has been compressed and the gases of combustion are exhausted from the chamber 76.

A fuel charge having been injected into the chamber 74, ignition of the compressed charge in the chamber 77 will cause the parts to move through the positions illustrated in FIG. 5 back to the positions illustrated in FIG. 1.

I claim as my invention:

1. In an engine, block means formed to provide four equiangularly spaced cylinders opening toward a common center, a composite piston reciprocable in each cylinder, each such piston comprising a main body open toward said center and having an axial port tapered away from said center and a plug reciprocable relative to said main body to open and close said port, a first drive piston reciprocable across said common center and cooperative with one diametrically opposed pair of said plugs, a second drive piston reciprocable across said common center and cooperative with the other diametrically opposed pair of plugs, link means connected at one end to said first drive piston and connected at the other end to said second drive piston, rotor means mounted on an axis perpendicular to the plane which is common to said cylinders, and means pivotally connecting the midportion of said link means eccentrically to said rotor means.

2. The engine of claim 1 in which each cylinder is closed at its end remote from said common center to define, with its piston, a combustion chamber, and means for injecting fuel into said combustion chambers successively at times when said pistons are retracted.

3. The engine of claim 2 in which each cylinder is provided with a fuel inlet port near its closed end, said port being closed by its associated piston at the initiation of combustion in its associated combustion chamber.

4. The engine of claim 3 in which each plug is formed with an exhaust port which is closed when said plug is in piston-port-closing position.

5. The engine of claim 3 including a one-way valve in said fuel inlet port closing said inlet port during combustion in its associated combustion chamber.

6. The engine of claim 1 in which each cylinder is counterbored to define, near its inner end, an outwardly facing stop to limit inward movement of said piston body and of said plug, said piston body being longer than said plug so that, under the influence of combustion pressure in any cylinder, the associated piston body and plug will move inwardly together until said body encounters said stop, whereafter said plug will continue to move inwardly until said plug encounters said stop, thereby opening the axial port of said piston body.
